[57] CLAIM

The ornamental design for a combined electric shaver and cover, as shown and described.

DESCRIPTION

FIG. 1 is a front, top and left-side perspective view of a combined electric shaver and cover showing our new design with the cover in place;

FIG. 2 is a right-side elevational view thereof, the left-side elevational view being a mirror image;

FIG. 3 is a rear elevational view thereof;

FIG. 4 is a front elevational view thereof;

FIG. 5 is a top plan view thereof;

FIG. 6 is a bottom plan view thereof;

FIG. 7 is a front elevational view of the cover;

FIG. 8 is an exploded perspective view similar to FIG. 1 with the cover separated from the shaver, the shaver being shown from the rear, left side, and top;

FIG. 9 is a rear elevational view of the shaver;

FIG. 10 is a left-side elevational view of the shaver, the right-side elevational view being a mirror image;

FIG. 11 is a front elevational view of the shaver;

FIG. 12 is a bottom plan view of the shaver;

FIG. 13 is a top plan view of the shaver;

FIG. 14 is a left-side elevational view similar to FIG. 10 with the socket rotated downwardly;

FIG. 15 is a front elevational view similar to FIG. 11 with the socket rotated downwardly; and

FIG. 16 is a bottom plan view similar to FIG. 12 with the socket rotated downwardly.
